UNITED STATES PATENT OFFICE.

JOHN V. CLARKE, OF WATERTOWN, NEW YORK.

BOX FOR THE STOP-COCKS OF SERVICE-PIPES.

SPECIFICATION forming part of Letters Patent No. 349,567, dated September 21, 1886.

Application filed April 6, 1886. Serial No. 198,041. (No model.)

To all whom it may concern:

Be it known that I, JOHN V. CLARKE, a citizen of the United States, and a resident of Watertown, in the county of Jefferson and State of New York, have invented certain new and useful Improvements in Boxes for the Stop-Cocks of Service-Pipes; and I do hereby declare that the following is a full, clear, and exact description of the invention, which will enable others skilled in the art to which it appertains to make and use the same, reference being had to the accompanying drawings, which form a part of this specification, and in which—

15 Figure 1 is a vertical sectional view showing the application of my improved box for the stop-cock of a service-pipe; and Fig. 2 is a similar view taken at a right angle to the section in Fig. 1, and showing a slight modification in the outer tube.

Similar letters of reference indicate corresponding parts in both the figures.

My invention has relation to boxes or tubes for the stop-cocks of water or gas service-pipes 25 which pass from the surface of the ground to a pipe below the ground, having a stop-cock for the purpose of cutting off the supply passing through the pipe; and it consists in the improved construction and combination of parts 30 of such a box or tube, as hereinafter more fully described and claimed.

In the accompanying drawings, the letter A indicates the stop-cock, which is provided with a screw-threaded neck, G, upon its upperside, 35 and which is provided with the head or handle K of the plug in the cock, by means of which handle the plug is turned. An outer tube, C, extends from the surface of the ground down to the cock, and the upper end of the tube is 40 provided with a removable screw-cap, B, and a shorter pipe, D, having a packing-ring, F, of rubber or similar elastic material around its upper end, fits within the outer tube and has its lower female screw-threaded end secured 45 upon the screw-threaded shoulder or neck of

the stop-cock. The shorter inner tube extends as far as the water in the ground is liable to rise in wet weather, and it will be seen that the inner tube being screwed to the stop-cock no water can enter at the lower end of 50 the tube, and the upper end of the tube is above the level to which the water in the ground is liable to rise, and at the same time the upper end of the tube is sliding within its packing within the tube, so that no water can possibly 55 enter, even if the water rises above the end of the inner tube. The inner tube sliding within the outer tube will allow the latter to move up or down in the ground, as it is liable to do during frosty weather, without injuring the inner 60 tube or the cock, and the tubes will always keep the head of the plug free from dirt or accumulated water, so that it may always be reached with a key or wrench and turned.

For the purpose of preventing the outer tube 65 from turning, the lower end of the same may be provided with a downwardly-extending lip, E, at one side, which lip will bear against the side of the cock and prevent the tube from turning when the screw-cap is secured upon its upper 70 end or removed. If the inner tube is sufficiently high to prevent any possibility of the water entering above it, the packing may be dispensed with at the upper end of the tube.

Having thus described my invention, I claim 75 and desire to secure by Letters Patent of the United States—

The combination, with a service-pipe stop-cock having a tube secured to the upper side, extending upwardly therefrom, of an adjustable capped tube provided at its lower end with a downwardly-projecting lip, substantially as and for the purpose set forth.

In testimony that I claim the foregoing as my own I have hereunto affixed my signature 85 in presence of two witnesses.

JOHN V. CLARKE.
